DESIGN FOR A CASKET LID

Carl A. Kuhlman, York, Pa., assignor to York
Hoover Corporation, York, Pa., a corporation
of Pennsylvania

Application November 6, 1944, Serial No. 116,183

Term of patent 14 years

(Cl. D19—1)

To all whom it may concern:

Be it known that I, Carl A. Kuhlman, a citizen of the United States, residing at York, in the county of York and State of Pennsylvania, have invented a new, original, and ornamental Design for Casket Lid, of which the following is a specification, reference being had to the accompanying drawing, forming part thereof.

In the drawing:

Figure 1 is a perspective view of a casket lid,
showing my new design.

Figures 2, 3 and 4 are views thereof respectively in plan, side, and end elevation.

I claim:

The ornamental design for a casket lid, as shown.

CARL A. KUHLMAN.
